DESIGN FOR A PICTURE CARRYING SERVICE BANNER

William G. Cook, Jr., Greenville, Pa.

Application June 26, 1942, Serial No. 107,350

Term of patent 3½ years

To all whom it may concern:

Be it known that I, William G. Cook, Jr., a citizen of the United States, residing at Greenville, in the county of Mercer and State of Pennsylvania, have invented a new, original, and ornamental Design for Picture Carrying Service Banner, of which the following is a specification, reference being had to the accompanying drawing, forming a part thereof.

The figure is a plan view of a banner showing my new design.

The dotted lines in the central part of the banner indicate in outline, where the picture will be inserted on the banner.

I claim:

The ornamental design for a picture carrying service banner, substantially as shown and described.

WILLIAM G. COOK, JR.
